UNITED STATES PATENT OFFICE.

CARL E. METHUDY, OF ST. LOUIS, MISSOURI, ASSIGNOR TO METHUDY ENAMEL RANGE CO., OF EAST ST. LOUIS, ILLINOIS, A CORPORATION OF ILLINOIS.

DESIGN FOR A GAS RANGE.

Application filed February 3, 1928. Serial No. 25,158. Term of patent 14 years.

To all whom it may concern:

Be it known that I, CARL E. METHUDY, a citizen of the United States, residing in the city of St. Louis and State of Missouri, have invented a new, original, and ornamental Design for Gas Range, substantially as shown in the accompanying drawing.

Fig. 1 is a perspective view of a gas range showing my new design.

Fig. 2 is an end elevation from the oven side.

Fig. 3 is a view showing the opposite end of the range.

The lining on the drawing indicates contrasting colors.

I claim:

The ornamental design for a gas range, substantially as shown.

CARL E. METHUDY.
